UNITED STATES PATENT OFFICE

101,185

DESIGN FOR A CURTAIN ENSEMBLE

Leon Gordon, New York, N. Y.

Application August 3, 1936, Serial No. 64,201

Term of patent 3½ years

To all whom it may concern:

Be it known that I, Leon Gordon, a citizen of the United States of America, residing in Manhattan, county of New York, and State of New York, have invented a new, original, and ornamental Design for a Curtain Ensemble, of which the following is a specification, reference being had to the accompanying drawing, forming part thereof, wherein,

The figure is a plan view of a curtain ensemble showing my new design.

The characteristic feature of my design resides in the skipper line lacings on the curtain, as shown.

I claim:

The ornamental design for a curtain ensemble, substantially as shown, and described.

LEON GORDON.
